UNITED STATES PATENT OFFICE.

PAUL P. COMMANDER, OF DOERUN, GEORGIA.

PRINTING MECHANISM.

Application filed September 15, 1924. Serial No. 737,840.

To all whom it may concern:

Be it known that I, PAUL P. COMMANDER, a citizen of the United States, residing at Doerun, in the county of Colquitt and State of Georgia, have invented a new and useful Printing Mechanism, of which the following is a specification.

The device forming the subject matter of this application is a printing mechanism 10 adapted to be used primarily for printing on boxes of fruit, the number of pieces of fruit in the box, the packer's number, or any other data which it may be desired to impress on the box. The invention aims 15 to provide a printing member so constructed that the type-carrying portion thereof may be swung upwardly against the box, to provide novel means for operating the printing member, to provide novel 20 means for inking the type on the printing member, and, generally, to improve and to enhance the utility of devices of that sort to which the invention appertains.

Although a preferred form has been 25 shown in the drawings, it will be understood that a mechanic, working within the scope of what is claimed, may make changes and alterations, without departing from the spirit of the invention.

30 In the accompanying drawings:—

Figure 1 shows in top plan, a device constructed in accordance with the invention, a portion of the bench or support being broken away; Figure 2 is a side elevation; Figure 3 is a perspective disclosing one of the type bars and attendant parts; Figure 4 is a section on the line 4—4 of Figure 2, parts being broken away; Figure 5 is a sectional elevation wherein the type bar has been brought up against the box which is to be imprinted; and Figure 6 is a section on the line 6—6 of Figure 1.

The printing mechanism forming the subject matter of this application contemplates 45 the provision of a support 1, which may be a packing bench of the sort disclosed in my co-pending application Serial Number 737,839, filed on the 15th day of September, 1924. The support or packing bench is not described in detail, because I know that one cannot claim the details of a packing bench, and the details of a printing mechanism in the same application. The support 1 embodies legs 3 merging into horizontal members 4 carrying any suitable means 5 for supporting a box 2 of the kind in which

oranges and other fruit are packed. Figure 5 will render it evident that this present application provides means for printing on the end of the box 2. The legs 3 are connected by an upper cross piece 6 and a lower cross piece 7, a brace 8 extending between the cross piece 7 and the supports 4, the brace being omitted in Figure 1, and elsewhere, to the end that the printing mechanism may not be obscured by mere bench details. There are guides 9 on the lower cross piece 7, the guides preferably being in the form of eyes.

Passing from bench construction to printing mechanism, it will be noted that operating members 10, in the form of plungers, are loosely mounted for vertical reciprocation in the guides 9, the plungers being provided at their lower extremities with pedals 11 which extend beneath the bench, at each side thereof, so that an operator on either side of the bench may actuate the printing means. The upper ends of the plungers 10 are inwardly offset, as shown at 12, and 70 terminate in eyes 14 located between nuts 15 and 16 on a pivot rod 17 having abutments 18 located inwardly of the nuts 16.

The inner ends of levers 19 are mounted 75 pivotally on the rod 17, between the abutments 18 and the nuts 16, the levers being fulcrumed intermediate their ends on a rod 20 connected at its ends by securing elements 21 with the legs 3. Tubular spacers 22 are mounted on the fulcrum rod 20 between 80 the inner edges of the legs 3 and the levers 19, and, cooperating with the abutments 18 on the pivot rod 17, hold the levers 19 for parallel swinging movement in vertical planes. The outer ends of the levers 19 85 are upwardly curved, as shown at 23, and are connected by securing members 25 to a carrier block 24. The parts 19—23—24 may be alluded to generally and briefly as a U-shaped lever fulcrumed intermediate its ends 100 on the support 1. In order to swing the ends 23 of the levers 19 downwardly from the printing position of Figure 5 to the inking position at Figure 2, a retractile spring 26 is connected at its ends to the carrier block 24 and to the lower cross piece 7 105 of the bench frame. The angles 46 of the plungers 10 are adapted to abut against the sleeves or spacers 22 to stop the levers 19 in the inking position of Figures 2 and 6.

The carrier block 24 is provided with any desired number of openings 27, spaced apart

longitudinally of the block and communicating with enlarged seats 28 formed in the upper surface of the block. The openings 27 of the carrier block 24 receive slidably, 5 the stems 29 of the type bars 30 carrying type 31. The upper ends of the stems 29 of the type bars 30 are enlarged as at 32 to form shoulders 53. Compression springs 33 are disposed about the parts 32 of the 10 stems of the type bars 30 and are located partly in the seats 28 of the carrier block 24, the springs abutting at their ends against the type bars 30 and against the carrier block 24. The springs 33 support the type 15 bars 30 yieldably when the type bars are brought up against the end of the box 2, as shown in Figure 5, but if enough pressure is exerted on the pedals 11, the shoulders 53 on the stems of the type bars may come 20 into contact with the carrier block 24 at the bases of the seats 28, thus forcing the type 31 against the end of the box 2 positively. The enlargements 32 in the stems of the type bars not only form the shoulders 53, 25 but, as well, conform closely but somewhat loosely to the springs 33, so that the springs will not tend to flex too much sidewise, when they are under compression. The upward movement of the type bars 30, responsive to 30 the springs 33, is limited by stop pins 34, which, being inserted through the lower ends of the stems 29, engage the lower surface of the carrier block 24. In order to prevent the stems 29 of type bars 30 from rotating in the carrier block 24, and in order to 35 position the type 31 properly with respect to the end of the box 2, the type bars slide in contact with an upstanding guide plate 35 secured at 36 to the carrier block 24.

40 Referring to the inking mechanism, it is to be observed that a substantially horizontal U-shaped frame 37 is held on the legs 3 of the bench frame by the securing elements 21 which engage the ends of the fulcrum rod 20. Although any suitable means 45 may be provided for inking the type 31, it is contemplated that recourse may be had to a known construction, including a pad 38 carried by the body 39 of a box, a lid 40 being hinged at 41 to the body, the pad resting 50 on the type 31, and the lid 40 extending downwardly within the rear portion of the frame 37, securing devices 42 connecting the lid to the frame 37. One of the securing devices 42 retains an upstanding spring tongue 43, overhanging the body 39 of the pad carrier, and adapted to be put under tension 55 by contact with the part 39, when the pad 38 is swung upwardly from the position of Figure 6 to the position of Figure 5, the element 43 being in substance a return spring for carrying the pad back into the position of 60 Figure 6 on the type 31, or, at least, being a means whereby the pad 38 is prevented 65 from being swung over too far to the right.

in Figure 5. The means for moving the pad 38 from the type-engaging position of Figure 6 to the position of Figure 5 embodies a curved arm or opener, held on the carrier block 24 by one of the elements 25 70 which attach the carrier block to the levers 19. The arm or opener 44 is adapted to work beneath an outstanding lip 45 on the body 39 of the pad carrier, and this lip may be made conveniently by simply bending 75 outwardly, one of the side walls of the box body 39 which holds the pad 38.

Assuming that the box 2 is in the position delineated in Figure 5, the operator presses downwardly on one of the pedals 11, the plungers 10 moving downwardly in the eyes 9, the levers 19 being tilted on their fulcrum 20. The curved opener 44, moving with the levers 19, rides beneath the lip 45 on the pad carrier 39 and swings the pad 38 out of the path of the type 31, the part 39 engaging the spring tongue 43 and putting the same under tension. The levers 19 carry the block 24 upwardly, along with the type bars 30, 85 into the position of Figure 6, and the box 2 90 is printed upon at one or more places, depending upon the number of type bars 30 that are used. When pressure on the pedal 11 is released, the spring 26 swings the levers 19 and carries the type bars 30 and the 95 carrier block 29 away from the box 2, the opener 44 retiring from beneath the lip 45 of the pad body 39, the pad assuming the position of Figure 6, under the action of the 100 spring tongue 43.

Not only may the number of articles in the box 2 be printed thereon, but, also, the box may be marked with the packer's number and other indicia tending to prevent fraud, these 105 details relating more to packing house management than to the operation of a printing device of any specified form.

What is claimed is:—

1. In a device of the class described, a support, a type lever fulcrumed on the support, type on the type lever, a swinging pad cooperating with the type, and an opener coacting with the pad to swing the pad away from the type when the lever is swung in one direction, the opener being carried by the lever, the opener having arcuate movement with respect to the fulcrum of the lever. 110
2. In a device of the class described, a support, a type lever fulcrumed on the support, type on the type lever, a swinging pad cooperating with the type, an opener coacting with the pad to swing the pad away from the type when the lever is swung in one direction, the opener being carried by the lever, and spring means cooperating with the pad to move the pad toward cooperating position with the type, the spring means being rendered active by the movement of the 115 pad away from the type. 120
3. In a device of the class described, a support, a type lever fulcrumed on the support, type on the type lever, a swinging pad cooperating with the type, an opener coacting with the pad to swing the pad away from the type when the lever is swung in one direction, the opener being carried by the lever, and spring means cooperating with the pad to move the pad toward cooperating position with the type, the spring means being rendered active by the movement of the 125 pad away from the type. 130

3. In a device of the class described, a support, a substantially horizontal frame projecting from the support, an inking means carried by the outer end of the frame, 10 a lever fulcrumed intermediate its ends on the support, the outer end of the lever being disposed within the frame, type carried by the outer end of the lever, and cooperating with the inking means, a depending plunger, means for mounting the plunger for right-line sliding movement on the support, and means for pivotally connecting the upper end of the plunger with the inner end of the lever.
- 15 4. In a device of the class described, a support, a fulcrum member carried by the support, a lever mounted to swing on the fulcrum member, type carried by the lever, a plunger mounted for reciprocation on the support and having an angle, the plunger being pivotally connected with the inner end of the lever, the angle in the plunger permitting the plunger to be located close to a 20 part of the support, and permitting the plunger to be connected to the lever at a considerable distance from the fulcrum member, the angle in the plunger cooperat- ing with the fulcrum member to limit the movement of the type-carrying end of the lever toward an inoperative position. 30
5. In a device of the class described, a support, a lever fulcrumed on the support for swinging movement from a downwardly inclined position to an upstanding inclined position, means for stopping the movement of the lever in said downwardly inclined position, marking means carried by the outer end of the lever, and means for operating the lever, the outer end of the lever being so inclined with respect to the 35 body portion of the lever that the marking means will print on the vertical end of a box carried by the support, when the lever is in its upstanding inclined position, said inclination of the outer end of the lever 40 with respect to the body portion of the lever serving to position the marking means in a substantially horizontal plane, for inking, when the lever is in said downwardly inclined position. 45
- 50

In testimony that I claim the foregoing as my own, I have hereto affixed my signature.

PAUL P. COMMANDER.
